REFRIGERATION CONTROLLER

William E. Whitney, Cambridge, Mass., assignor,
by mesne assignments, to Stator Corporation,
a corporation of Rhode Island

Application January 15, 1938, Serial No. 185,193

21 Claims. (Cl. 62—2)

The present invention relates to an improved arrangement of refrigerating systems and of control devices suitable for refrigerating systems.

Certain refrigerating systems are heat operated and depend upon the continued input of heat to assure the maintenance of different pressures in different parts of the system. For example, a system of the type disclosed in the United States Patent No. 1,761,551 to Eastman A. Weaver provides an aspirator assembly for pumping refrigerant from a low pressure evaporator to a condenser. In a system of this character, if the operation of the aspirator is interrupted, as when the boiler pressure drops below a definite point, the condenser and evaporator pressures are equalized by vapor flowing from the condenser to the evaporator. This vapor unnecessarily warms the evaporator and food compartment, thus reducing refrigerating efficiency.

As disclosed in the copending application Serial No. 171,325 of Lyman F. Whitney, now matured into Patent No. 2,180,447, refrigerating systems of this character, which employ mercury as a propellant and which employ an aqueous refrigerant, may at times be characterized by the development of an objectionable or deleterious sludge. One factor which may cause the formation of such sludge is the flow of mercury vapor directly from the aspirator assembly to the evaporator. Under normal operating conditions, such "blow-back" of the propellant is an extremely unlikely occurrence, but it may occur when normal operation of the aspirator is about to be started or after such operation is interrupted.

If a system of this character is regulated by a conventional thermostatic control, the operation of the aspirator may be frequently interrupted, so that pressures in the condenser and evaporator may be frequently equalized and so that the tendency toward sludge formation is increased.

The present invention provides a system of the general character described, with an associated control means normally effective in permitting the continuous operation of the aspirator. Thus the pressure difference between the evaporator and condenser is maintained, sludge formation due to blow-back from the aspirator assembly into the evaporator is avoided, and refrigerating efficiency is also somewhat enhanced.

More particularly, the present invention permits the attainment of these desirable results with a refrigerator including an electrically operated heater. In addition, however, the present invention provides a control arrangement allowing the gradual variation in the average rate of

electrical input to the system in response to the temperature of the food compartment or the cooler without necessitating the waste of electricity by the use of rheostats or the like.

Further features of the invention relate to the provision of control means to maintain a uniform temperature or the like under widely varying conditions of operation and widely varying room temperatures, to permit manual adjustment of the range of operation when desired, and particularly, in the case of refrigerators, to afford means for automatically terminating a defrosting period.

In one respect this invention involves clock mechanism or other timed means for varying energy input during recurrent periods of time or cycles, as by causing a heater to operate for a period in each succeeding three-minute cycle or the like, together with means for varying the lengths of said periods in response to the temperature of the food compartment or other condition incident to the refrigeration. For example, under certain conditions of operation, the timed means may cause the apparatus to operate during one minute out of each successive three-minute cycle, and under other conditions requiring more refrigeration, the timed means may cause the apparatus to operate during two minutes out of every three-minute cycle. Thus while electricity is supplied to the system at constant voltage, the average rate of supply may vary over a substantial period of elapsing time. Preferably the apparatus is controlled through the medium of an electric switch with the timed means operating the switch, that is, opening and/or closing the switch, through the medium of a cam or the like.

In another aspect the invention involves a snap switch in a casing with an actuator extending outside the casing for actuating the switch, a cam or other timed means for operating the switch during recurrent periods of time, and thermostatic or other means for varying the length of the periods by relative displacement of the casing and cam with respect to each other. Preferably the timed means operates on one contact of the switch, as by engagement with said actuating member, and the thermostat operates on the other contact of the switch, as by engagement with said casing, although both may operate on the same contact, as by causing the thermostat to move the timed means and contact relatively to each other or causing the timed means to move the thermostat and contact relatively to each other.

In the preferred embodiment the switch casing is movably mounted with a spring or other yielding means urging it toward the cam and the thermostat controls a stop which limits the movement of the casing toward the cam. While the stop may be either advanced or retracted in response to increase of temperature, expansion of the thermostat preferably advances the stop to shorten the length of the recurrent periods of actuation of the switch by the cam.

In still another aspect this invention involves a movable switch and a thermostat for moving the switch, together with a latch for holding the switch out of operative relation to the thermostat and trip mechanism associated with the thermostat and latch for restoring the operative relationship when the temperature of the thermostat reaches a predetermined point.

For the purpose of illustration a typical embodiment of the invention is shown in the accompanying drawings in which

Fig. 1 is a top plan view of my improved control device;

Fig. 2 is a rear elevation of the same with the parts in normal operating positions and with the rear cover plate removed, a part being shown in section;

Fig. 3 is a rear elevation of the same with the parts in defrosting position and with the front cover plate omitted;

Fig. 4 is a rear elevation, with both the front and the rear cover plates removed, showing the parts in the positions which they occupy immediately following defrosting;

Fig. 5 is an end elevation viewed from the left-hand end of the preceding figures;

Fig. 6 is a section on line 6-6 of Fig. 2;

Fig. 7 is a plan view of the electric switch with the cover removed;

Fig. 8 is a plan view of the inside of the switch cover;

Fig. 9 is a side elevation of the switch assembly showing a part in section and showing a part of the switch operating lever; and

Fig. 10 is a diagrammatic view of a refrigerating system with which the control device is combined, parts being shown in section.

The preferred control device chosen for the purpose of illustration comprises a front cover plate 1, a rear cover plate 2, an angle member 3 interconnecting the cover plates at the top, a channel member 4 interconnecting the cover plates at the bottom, and a pivot pin 5 bridging the space between the cover plates. Pivotally mounted on the pin 5 is a yoke 6 carrying between its legs an electrical switch comprising a casing 7, a cover 8, terminal screws 9 and 10, and an actuator 43, the casing being mounted in the yoke by means of screws 11 and the cover being secured to the casing by means of screws 12 (Fig. 2). The yoke 6 is yieldingly urged in a counter-clockwise direction by means of a spring 13; and the counter-clockwise rotation of the yoke is limited by a stop controlled by a thermostat comprising bellows 14.

The aforesaid stop comprises a channel-shaped member 15 having its flanges directed upwardly with the ends 16 of the flanges extended upwardly to pivot the member on the pin 5, the extensions 16 fitting between the ends of the yoke 6 as shown in Fig. 1. Fast to the free end of the member 15 is a U-shaped yoke 17 having upwardly extending arms 18 in the path of the two legs of the yoke 6 and having a downward extension 18' which is L-shaped and which has fast

to the free end thereof a rounded bearing member 19. Fast to the right-hand end of the member 15 (Figs. 2, 3 and 4) is an arm 20 which extends outwardly to a spring 21, the spring serving to hold the member 15 against the contact button at the upper end of the bellows 14. As the bellows expands upwardly it lifts the stop 15-17-18 against the action of the spring 21, and if the yoke 6 is seated against the upper ends 18 of the stop it also lifts the yoke against the action of spring 13. The bellows 14 is enclosed by sleeve 22 fast to the channel member 4 and the lower end of the bellows is provided with a nipple 23 for attachment to the fluid tube of the thermostatic system.

As shown in Figs. 5 and 6 the lower end of the bellows 14 rests on a bifurcated lever 24 which is fulcrumed in the back plate 2 at 25 and which has an opening in its forward end for a rod 26. Threaded on the lower end of the rod is an adjusting nut 27 seating upwardly against a recess in the lower side of the lever 24. The upper end of the rod 26 is pivoted at 28 to the lower end of an L-shaped member 29, the other end of which is pivotally mounted on the pin 5 as shown in Figs. 1 and 2. The under side of the member 29 is provided with a shoulder 30 upon which bears a cam 31 fast to the shaft 32 which carries on its outer end an adjusting knob (Fig. 1). By rotating the knob 33 the bellows 14 is lifted by the lever 24 until the shoulder 30 drops off the end of the cam (Fig. 2) whereupon the bellows may again be lifted by continued rotation of the knob 33 in the same direction.

Disposed between the switch 7-8 and the stop 15-17 is an L-shaped lever 34 having an upturned end pivoted on end 36 of the pin 5 (Figs. 1 and 5). Beneath the free end of the lever 34 is a cam 35 rotating on a pin 36 mounted in the front and back plates 1 and 2 as shown in Figs. 1 and 5. Fast to the rear end of the cam 35 is a gear wheel 37 whose periphery overlaps the opening 38 in the back plate as shown in Fig. 3. The gear 37 is driven by clock mechanism 39 (Figs. 5 and 6) mounted on the rear of the back plate 2 and having a shaft 40 extending forwardly through the opening 38 with a pinion on the end of the shaft meshing with the gear 37 (Fig. 3). Thus rotation of the cam 35 raises and lowers the lever 34 resting thereon.

As shown in Figs. 7, 8 and 9 the electric switch comprises a stationary contact 41, a movable contact 42, a stop 54 and a plunger 43 actuated by the lever 34 for moving the contact 42 from the contact 41 to the stop 54. As shown in Fig. 7 the contact 42 is bifurcated and the free ends associated with the contact 41 are, in the process of manufacture, slightly pinched together toward each other and held in this position by a cross strap 55, as well as being bent as shown in Fig. 9. Consequently pressure on the contact 42 by the plunger 43 causes the contact 42 to snap from the position shown in Fig. 9 to a position wherein the free ends of the contact 42 curve downwardly (Fig. 9) into engagement with the stop 54, release of pressure by plunger 43 permitting the contact 42 to snap back into the circuit-closing position shown in Fig. 9.

In the normal operation of the device the cam 35 opens the switch through the medium of lever 34 and plunger 43 once during each revolution of the cam, the switch remaining open for a period of time whose length depends upon the position of the stop 15-17 as determined by the thermostatic bellows 14. If the bellows is ex-

panded to raise the stop, the switch is opened for a short interval of time and if the bellows is contracted to permit the spring 21 to lower the stop the switch is opened for a longer interval of time. After the cam has opened the switch through the medium of the lever 34, the plunger 43 lifts the yoke 6 against the action of the spring 13.

For defrosting purposes the following mechanism is provided. Pivoted to the frame member 3 at 44 is a depending L-shaped arm 45 having a cam surface 46 at its lower end for cooperation with the bearing 19 on the yoke 17 and having a lateral lug 47 intermediate its ends. Journaled in the front plate 1 is a shaft 48 having on its forward end an actuating knob 49 and on its rearward end an arm 50 provided with a notch 51, a shoulder 52 and a laterally projecting pin 53. When it is desired to defrost, the knob 49 is turned to swing the arm 50 in a counter-clockwise direction (Fig. 2) until the lug 47 drops into the recess 51, the parts then occupying the positions shown in Fig. 3. In swinging the arm 50 to defrosting position, the pin 53 engages the switch-actuating lever 34, thereby opening the switch and lifting it to the position shown in Fig. 3. With the source of energy shut off from the refrigerating apparatus the bellows 14 gradually lifts the yoke 17-18 to the position shown in Fig. 4 whereupon the arm 45 is disengaged from the arm 50 by engagement of the bearing 19 against the cam surface 46. The arm 50 then swings back to its normal position shown in Figs. 2 and 4 and normal operation of the apparatus is resumed.

A control device of the type herein described may be employed in combination with various types of refrigerating systems such as motor driven apparatus, or apparatus provided with a fuel burning heater. In the latter case the switch 7 may control the heater by means of an electromagnetic valve. A control device of this type however is particularly advantageous when combined with a refrigerating system of the type disclosed in the above-identified patent and when the characteristics of the control device and the systems are so co-related that continuous operation of the aspirator assembly is normally permitted. Especially when a system of this type is provided with an electric heater, such a control device may be combined with the system to effect continued operation of the aspirator without necessitating the waste of electrical energy and while permitting extremely accurate control of the refrigerating apparatus in accordance with the temperature of the food compartment and/or evaporator.

Fig. 10 discloses a system of this type which is provided with a boiler 101 affording a relatively large cylindrical recess for the reception of a removable cartridge 102 containing an electrical resistance element. The boiler 101 may afford a thin mercury containing jacket about the sides and bottom of the cartridge receiving recess and may provide a chamber 101^a of substantial size above the cartridge, this chamber communicating with the jacket. When electrical energy is supplied to the heating cartridge 102 mercury is vaporized in the boiler 101 and the resulting vapor passes upwardly through the riser pipe 105 and its branches 105^a and 105^b to the first and second stage aspirator nozzles 106 and 116 respectively. These nozzles form portions of aspirator assemblies 107 and 117 respectively. The assembly

107 affords a mixing chamber 108 connected by a vapor duct 109 to the upper part of an evaporator 110 which contains a body of liquid refrigerant. A suitable aqueous refrigerant such as water or a mixture of water with a suitable anti-freeze agent such as methyl cellosolve and/or ethyl diamine may be provided in the evaporator 110. When mercury vapor issues from the nozzle 106 at high velocity, the mixed vapors pass into a funnel 111 where the refrigerant is compressed and mercury is condensed. The compressed refrigerant vapor passes from the lower end of the funnel 111 into an interstage cooler 120 which is provided with cooling means such as fins 113. The vapor passes from the interstage cooler 120 through a duct 114 to a connection with the mixing chamber 118 of the second stage aspirator assembly where the mercury vapor from the nozzle 116 is effective in further pumping and compressing the refrigerant vapor as it passes through the funnel 121. The compressed refrigerant vapor flows upwardly from this funnel through a duct 122 to a refrigerant condenser 123 which may conveniently be disposed at the upper part of the system.

The aspirator assemblies are provided with jackets 115 and 125 which may contain a suitable volatile coolant, such as alcohol or a mixture of alcohol with a minor percentage of acetone. Ducts 130 and 130^a extend upwardly from the jackets 115 and 125 respectively to receive alcohol vapor therefrom, the upper parts of these ducts being provided with cooling fins and thus affording condensers which form heat dissipators for the funnels. In order to facilitate the dissipation of heat through these condensers, the ducts 130 and 130^a may preferably be evacuated so that substantially all of the air is removed therefrom. For this purpose suitable evacuating and sealing connections 133 may be connected to chambers 131 and 131^a at the upper ends of the ducts 130 and 130^a respectively. The chambers 131 and 131^a increase the volumetric capacities of the vapor-containing portions of the heat dissipators and make the same less sensitive to minor leakages of air.

The refrigerant condenser 123 is also provided with an evacuating and sealing connection 133' similar to the connections 133, so that the refrigerating system may be evacuated when it is installed and so that the evaporator 110 may operate at a low absolute pressure. For example, the pressure in the evaporator may be of the order of 4 mm. absolute at 0° C.

The condenser 123 is provided with any suitable cooling means such as heat dissipating fins and its lower end is connected to a return duct 135 providing one leg of a trap 136, the opposite leg of which is connected by a short duct 137 to the evaporator 110. The trap 136 may contain a body of the propellant e. g. mercury, and the pipe 135 is arranged so that the condensed refrigerant piles up in a column above the mercury in the trap until some of the refrigerant can pass through the trap and thus return to the evaporator. It is evident that the mercury in trap 136 is effective in substantially balancing the difference between the evaporator and condenser pressures.

Condensed mercury may be received from the first stage funnel by a drain 140 which is connected to a drain 141 receiving mercury from the second stage funnel. Drain 142 receives condensed mercury from the first stage head 108 and is connected to a drain 143 receiving mercury

from the second stage head 118. The lower part of the drain 143 is connected to the drain 141. The lower part of the latter is connected to the bottom of the boiler 101 and contains a column of mercury to balance the boiler pressure.

5 A trap 150 is connected to the bottom of the evaporator 110 to receive stray mercury particles therefrom and the opposite leg of this trap has a connection 151 with the duct 143.

10 Electric energy may be supplied to a system of this character by leads 160 and 161, the latter being connected directly to one side of the cartridge 102 having a branch 162 connected to one side of the clock 39 of the control device shown in Figs. 1 to 9. The opposite side of this clock is connected by a lead 163 to the lead 160. The lead 160 is connected to one side of the switch 7 as shown in Fig. 9 and a lead 165 extends from the opposite side of the switch to the cartridge 15 20 25 102.

25 The bellows 14 is connected by a tube 167 to a thermostatic bulb 168 which may be arranged in the food compartment and in the region of evaporator 110. Accordingly the pressure within 30 the thermostatic device i. e. the bulb 168, tube 167 and bellows 14, varies in accordance with the temperature of the food compartment and the evaporator. When this temperature increases the pressure within the thermostatic device 35 causes the bellows 14 to expand thus lifting the member 15 so that the switch 7 is opened for a smaller fraction of each cycle of the control device corresponding to each revolution of the cam 35. Thus, under these conditions, the portion of 40 the operating cycle during which heat is supplied to the boiler 101 is increased and accordingly over a substantial period of time, the average electrical input is correspondingly increased. It is evident that the switch 7 as shown may be arranged directly in series with the cartridge 102 so that when the switch is closed, heat is being supplied to the mercury within the boiler 101.

45 The boiler 101 and the aspirator assemblies 107 and 117 preferably are enclosed in a suitable heat insulating casing comprising a metal housing 170 containing discrete insulating material 171. Thus during the short intervals during which the supply of current to the cartridge 102 is interrupted, there is but a slight change in the temperature of the mercury circuit and of the boiler. The mercury containing portions of the refrigerating system and the various factors of the control device accordingly may be so interrelated that under normal operating conditions i. e. when the room temperature is above 60° F. continuous operation of the aspirator assembly is maintained despite the frequent interruptions to the input of electrical energy. Thus between successive switch-closing periods there may be only a moderate decrease in the pressure within the boiler 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

the mercury vapor through the duct 109 into the evaporator 110 is accordingly avoided. Thus a tendency to form sludge which might otherwise be present is eliminated.

Furthermore the control device permits a very slight variation in the average amount of energy being supplied to the cartridge 102 and the boiler 101 in response to a small change in the temperature of the bulb 168, so that a very close and accurate control of the refrigerating system is afforded. As a consequence the maximum pressures within the system may be lower than would be the case with an intermittently operating system. If a system of the present type were to be provided with a conventional thermostatic control effective to cause the operation of the aspirator assembly for a period of substantial length and then interruption of such operation for a period of substantial length, higher boiler pressures would be necessary than with the present arrangement. Such a higher boiler pressure might result in an appreciable noise when the system first resumed operation. The present arrangement however avoids such a disadvantage.

Preferably the thermostatic device 14—167—168 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

It is thus evident that the present invention permits the continuous operation of a refrigerating system of the aspirator type at normal room temperature, thus avoiding unnecessary heating of the evaporator and reducing the likelihood of sludge formation. It is furthermore evident that the present invention affords an unusually sensitive and accurate control for the refrigerating apparatus, which avoids the undesirable lag which is characteristic of a device wherein a switch is directly opened and closed by a thermostatic device. It is furthermore evident that a device of this character permits the close and accurate regulation of the average rate of supply of energy to the system without necessity for wasting electricity as would be the case were a rheostat or rheostats employed.

While for the purpose of illustration, I have disclosed herein a simple refrigerating system embodying the principles of the present invention, it is to be understood that a more highly developed system such as that shown in the above-identified co-pending application can be combined with my improved control device to afford the same desirable results. It is furthermore evident that if desired, a relay may be controlled by the switch 7 in order in turn to control the supply of energy to the heater 102.

It should be understood that the present disclosure is for the purpose of illustration only and that this invention includes all modifications and equivalents which fall within the scope of the appended claims.

I claim:

1. Refrigerating apparatus of the heat-operated type comprising an electric heater, a refrigerant circuit including a cooler through which refrigerant is circulated in response to operation of the heater, a switch controlling the flow of electricity to said heater, a controller for the switch operable in brief repetitive cycles each including a switch closing period, and a thermostatic device to vary the effect of the controller on the switch in accordance with the temperature of the region of the cooler so that the lengths of intervals between said periods in successive cycles increase and decrease respectively as the temperature of said region falls and rises, the maximum lengths of said intervals being so short that continuous, uninterrupted circulation of the refrigerant is normally maintained.
2. Refrigerating apparatus comprising a cooler, a condenser, an aspirator for pumping refrigerant vapor from the cooler to the condenser, a boiler for supplying propellant vapor to the aspirator, an electric heater for said boiler, and controlling means for said heater responsive to the temperature of the region of the cooler for supplying electricity to said heater at constant voltage but at a varying average rate dependent upon the temperature of said region, the minimum average rate being high enough to maintain continuous, uninterrupted pumping of refrigerant in the aspirator.
3. Refrigerating apparatus comprising a refrigerant circuit including a condenser and a cooler containing a body of liquid refrigerant, a propellant circuit including a boiler and an aspirator where refrigerant vapor is pumped from the cooler to the condenser, said boiler containing a body of propellant fluid which, upon straying to the cooler, may interact with the refrigerant to form a deleterious sludge, an electric heater for said boiler, a switch controlling the flow of electricity to said heater, a controller for the switch operable in brief repetitive cycles, and thermostatic means responsive to the temperature of the region of the cooler for varying the effect of the controller on the switch so that the switch is closed during a period in each cycle, the duration of which depends upon the temperature of said region, the intervals between said periods being so short, that continuous, uninterrupted circulation of the refrigerant is normally maintained by said aspirator, whereby automatic control of refrigeration is afforded but direct flow of propellant vapor to the cooler is substantially prevented, thus impeding sludge formation in the cooler.
4. Refrigerating apparatus comprising a refrigerant circuit including a condenser and a cooler containing a body of liquid refrigerant, a propellant circuit including a boiler and an aspirator for pumping refrigerant vapor from the cooler to the condenser, said refrigerant circuit being open and uninterrupted between the cooler and condenser and the pressure of the propellant vapor normally being effective in maintaining a higher pressure in the condenser than in the cooler, an electric heater for said boiler, a switch controlling the flow of electricity to said heater, and control means for said switch including an element responsive to the temperature of the region of said cooler, said means being effective in closing and opening said switch during brief recurrent cycles controlled so that the total fraction of elapsing time during which the switch is closed varies in

accordance with the condition of the temperature responsive element, the lengths of intervals of interruption to the flow of electricity to the heater being so short that operation of said aspirator is not interrupted and accordingly flow 5 of refrigerant vapor from the condenser to the cooler is not permitted.

5. Method of refrigeration comprising supplying electrical energy to vaporize a propellant, entraining refrigerant vapor from a body of 10 liquid refrigerant in a stream of the resulting propellant vapor and pumping the refrigerant vapor to a region of higher pressures, while supplying electrical energy to vaporize the propellant at constant voltage but in brief recurrent 15 periods, varying the total fraction of the elapsing time occupied by said periods in accordance with the temperature of the region of said body, thereby to maintain the temperature of the region of said body within close limits, but maintaining 20 said fraction great enough and intervals between said periods short enough to assure continuous pumping of the refrigerant.

6. Refrigerating apparatus comprising a refrigerant circuit including a condenser and a 25 cooler containing a body of liquid refrigerant, a propellant circuit including a boiler and a part in common with the refrigerant circuit where propellant vapor is effective in entraining and compressing refrigerant vapor, said propellant 30 circuit also including a duct extending downwardly to the boiler and normally containing a column of liquid propellant to balance the boiler pressure, an electric heater for said boiler, a switch controlling the flow of electricity to said 35 heater, and control means for said switch including an element responsive to the temperature of the region of said cooler, said means closing and opening said switch during brief recurrent cycles controlled so that the height of said 40 column fluctuates less than 15% during a single cycle.

7. A circuit controller comprising a casing, a snap switch within the casing, an actuator extending outside the casing for actuating the switch, means for operating said actuator during recurrent periods of time, and thermostatic means for varying the length of said periods by relative displacement of said casing and means with respect to each other.

8. A circuit controller comprising a switch casing, a snap switch inside the casing, a switch-actuating member extending through the casing, means for actuating said member during successive periods, a support for said casing, said casing and means being relatively movable to vary the duration of said periods by changing the operative relationship between said member and means, means yieldingly tending to change said relationship, and an adjustable stop limiting the 60 action of said means.

9. A circuit controller comprising a switch casing, a snap switch inside the casing, a switch-actuating member extending through the casing, means including a cam for actuating said 65 member, a support for said casing, said casing and cam being relatively movable to vary the operative relationship between said member and cam, a spring tending to change said relationship, and a thermostatic stop limiting the action 70 of said spring.

10. A circuit controller comprising a switch casing, a snap switch inside the casing, a switch-actuating member extending through the casing, means for actuating said member during suc- 75

cessive periods, a support for said casing, said casing and means being relatively movable to vary the duration of said periods by changing the operative relationship between said member 5 and means, a bearing member between said member and means which is movable relatively to said casing and means, means yieldingly tending to change said relationship, and an adjustable stop limiting the action of said last 10 means.

11. A circuit controller comprising a switch casing, a snap switch inside the casing, a switch-actuating member extending through the casing, means for actuating said member during successive periods, a pivotal support for said casing, 15 said casing and means being relatively movable to vary the duration of said periods by changing the operative relationship between said member and means, a pivoted bearing member between 20 said member and means which is coaxial with said pivotal support, means yieldingly tending to change said relationship, and an adjustable stop limiting the action of said last means.

12. A circuit controller comprising a switch 25 casing, a snap switch within the casing, a switch-actuating plunger extending through the casing, a cam rotatable about an axis for actuating said plunger during successive periods, a movable support for said casing for varying the duration of 30 said periods by moving said plunger toward and from said axis, a spring urging the casing toward the cam, and an adjustable stop limiting the action of said spring.

13. A circuit controller comprising a switch 35 casing, a snap switch within the casing, a switch-actuating plunger extending through the casing, a cam rotatable about an axis for actuating said plunger during successive periods, a movable support for said casing for varying the duration of 40 said periods by moving said plunger toward and from said axis, a spring urging the casing toward the cam, a stop for limiting the action of said spring, and a thermostat for moving said stop counter to said spring in response to increase of 45 temperature.

14. A circuit controller comprising a switch casing, a snap switch within the casing, a switch-actuating plunger extending through the casing, a cam rotatable about an axis for actuating said 50 plunger during successive periods, a movable support for said casing for varying the duration of said periods by moving said plunger toward and from said axis, a spring urging the casing toward the cam, and a thermostatic stop limiting the action of said spring.

15. A circuit controller comprising a switch casing, a snap switch within the casing, a switch-actuating plunger extending through the casing, a cam for actuating said plunger during successive 60 periods, a pivotal support for said casing for varying the duration of said periods by moving said plunger toward and from the cam, a spring urging the casing toward the cam, a pivoted stop coaxial with said support for limiting the action 65 of said spring, and means for swinging said stop counter to said spring thereby to move said plunger away from said cam.

16. A circuit-controller comprising a switch, a movable support for the switch, a thermostat 70 for actuating the switch, timed means for actuat-

ing the switch periodically, a latch for said support to hold the switch out of operative relation to said thermostat and timed means, and trip mechanism associated with said thermostat and latch for restoring said operative relationship of 8 the switch to both thermostat and timed means when the temperature of the thermostat reaches a predetermined point.

17. A circuit controller comprising a switch, a movable support for the switch, a thermostat 10 for actuating the switch, means yieldingly urging the switch toward the thermostat, a stop for limiting the action of said means, the thermostat acting on the switch through the medium of said stop, a latch for said stop to hold the switch 15 out of operative relation to the thermostat, and trip mechanism associated with said thermostat and latch for restoring said operative relationship 20 when the temperature of the thermostat reaches a predetermined point.

18. A refrigeration controller comprising a cover plate, means normally concealed by said plate for increasing refrigeration during recurrent periods of time, means for varying the length of said periods in response to the conditions of 25 refrigeration, and means for adjusting said last means including a manually movable part disposed outwardly of said cover plate.

19. A circuit-controller comprising a switch 30 casing, a snap switch inside the casing, a switch-actuating member extending through the casing, a cam for actuating said member during successive periods, a support for said casing, said casing and cam being relatively movable to vary 35 the duration of said periods by changing the operative relationship between said member and cam, means yieldingly tending to change said relationship, a stop limiting the action of said means, and an automatic regulator for moving said stop.

20. A circuit controller comprising a switch casing, a snap switch inside the casing, a switch-actuating member extending through the casing, means for actuating said member, a support for 45 said casing, said casing and cam being relatively movable to vary the operative relationship between said member and cam, a spring tending to change said relationship, a stop limiting the action of said spring, an automatic regulator for moving said stop, and means for manually adjusting the stop through the medium of said 50 regulator.

21. Refrigerating apparatus of the heat-operated type comprising an electric heater, a refrigerant circuit including a cooler through which refrigerant is circulated in response to operation of the heater, a circuit controller for said heater comprising a switch, a movable support for the switch, a thermostat for actuating the switch, timed means for actuating the switch periodically, a latch for said support to hold the switch out of operative relation to said thermostat and timed means, and trip mechanism associated with said thermostat and latch for restoring said operative relationship of the switch to both thermostat and timed means when the temperature of the thermostat reaches a predetermined point.
